Samuel F. Stoke,

UNITED STATES PATENT OFFICE.

DANIEL LEE MONROE AND SAMUEL FRANCIS STOKE, OF BLOOMFIELD,
IOWA.

FOUNTAIN AUGER-POWER AND TILE-Injector.

SPECIFICATION forming part of Letters Patent No. 369,545, dated September 6, 1887.

Application filed February 25, 1887. Serial No. 228,884. (No model.)

To all whom it may concern:

Be it known that we, DANIEL LEE MONROE and SAMUEL FRANCIS STOKE, citizens of the United States of America, and residents of 5 Bloomfield, in the county of Davis and State of Iowa, have invented a Fountain Auger-Power and Tile-Injector, of which the following is a specification.

Heretofore the method of securing water (in 10 the absence of springs or creeks) has been to dig or bore perpendicularly into the earth and raise the water thus found to the surface by means of pumps or buckets.

The object of this invention is to bore into 15 the ground at the base of hills or ground-swells in a horizontal direction, for the purpose of securing a continuous flow of water for stock and other purposes, thereby obviating the labor of raising it from perpendicular 20 wells by the old methods. To accomplish this purpose we have invented a method of constructing such wells and a machine for accomplishing such construction, which is called the "fountain auger-power and tile-in- 25 jeector," a drawing of which is presented on Sheets 1 and 2 accompanying this specification.

Our method of constructing such wells is as follows: first, to bore horizontally into the 30 ground by means of a boring-point and hollow shaft; then to introduce tile into the bore of the shaft, and then, holding said tile against retraction by a crowd or stay rod, to withdraw the shaft by unscrewing it from the point, 35 which is thus left in the ground. The mechanical instrumentalities which we employ for this purpose are described as follows:

In the drawings, Figure 1 is a plan view of the machine. Fig. 2 is a side elevation. Figs. 40 3 to 8 show details.

On Sheet 1, Fig. 1, H represents frame of machine. T T represent taps in frame H, through which the screws v v pass, which screw-shafts are connected by the flanged rotating bar B. u u on same shaft represent smooth bearings designed to throw the machine out of gear when withdrawing auger-shaft F by means of the chain L, Fig. 2, which chain passes around the shaft P, which is

turned by the lever K, which is bolted to the 50 cap J. I represents the master-wheel, which meshes into or turns the wheel C, which communicates a rotary motion to the flanged bar B and its attachments v v and u u. A A represent bridge-trees, in which rest the gudgeons 55 D D. O represents a step on which the shaft P rests. M M represent the supports on which rests the cap N.

Fig. 3, Sheet 2, is a sectional view of wheel C, taken upon line y y of Fig. 5, showing the 60 gudgeon-block D, the flanged bar B in section, and friction-rollers E in gudgeon-block D. X represents slot in center of wheel C, through which the flanged bar B passes.

Fig. 4 shows section of gudgeon D, the 65 square part of which fits in wheel C.

Fig. 5 is designed to represent a sectional part of wheel C upon line w w of Fig. 3, showing friction-rollers E and section of flanged bar B adjusted between friction-rollers in gudgeon- 70 block D.

Fig. 6 represents wheel C, showing the gudgeon D, which revolves in bridgertree A.

Fig. 7 shows uncoupled sections of hollow auger-shaft F and auger-head G.

Fig. 8 shows the manner of withdrawing the auger-shaft F, leaving the auger-head G in the ground on completion of the boring; also, sections of tiling S S S, injected through the hollow shaft F, and held in place by the crowd 80 or stay rod R while the hollow shaft F is being withdrawn by the chain L.

The swell on the forward part of v, beyond u, is designed to represent a short coupling connecting boring-shaft F by screwing 85 thereon.

We are aware that levers and wheels are old devices; but

What we claim as new, and for which we desire to secure Letters Patent, is—

1. The herein-described method for introducing tile horizontally into the ground, which consists in boring horizontally into the ground by a boring-point and hollow shaft, passing the tiles in succession through said hollow 90 shaft, and then removing said shaft, substantially as described, and for the purpose set forth.

2. The combination of the boring-point, the sections of hollow shafting detachable from said point, the stay-rod, the shaft P, chain L, and lever K, substantially as set forth.
- 5 3. The combination of the wheel C, provided with the gudgeons D and the friction-rollers, the flanged bar B, having the threaded portions v v, the smooth portions u u, and the taps T, substantially as set forth.

DANIEL LEE MONROE.
SAMUEL FRANCIS STOKE.
